UNITED STATES PATENT OFFICE.

CLARENCE E. FLORKEY, OF DAYTON, OHIO, ASSIGNOR TO THE SCHIEBLE TOY AND NOVELTY COMPANY, OF DAYTON, OHIO, A CORPORATION OF OHIO.

WHEELED TOY.

Original application filed November 3, 1922, Serial No. 598,902. Divided and this application filed October 8, 1923. Serial No. 667,379.

To all whom it may concern:

Be it known that I, CLARENCE E. FLORKEY, a citizen of the United States, residing at Dayton, in the county of Montgomery and State of Ohio, have invented certain new and useful Improvements in Wheeled Toys, of which the following is a specification, reference being had therein to the accompanying drawing.

10 My invention relates to toys, and in particular to power toys.

It is the object of my invention to provide a toy representing an automobile which can be economically manufactured in quantities out of a minimum number of pieces.

15 It is my object to provide a toy which will be rigid and strong and which will be adaptable to a pull toy and also be adaptable to a power toy which is preferred. The source of power is immaterial, but I prefer to employ a friction drive.

20 It will be understood that in the manufacture of toys where the amount of profit per toy is small it is essential that the production in large quantities be through dies. Because of the great expense of the dies, it is necessary to reduce the number of parts of any toy to the minimum. It is also essential to reduce the amount of stock used so that 25 it is a matter of considerable importance to economically utilize the stock and so design the several parts that there will be the least waste.

25 It is also essential to have the toys simulate the appearance of actual articles of commerce as nearly as possible.

30 It is an additional object to provide a blank so laid out that when it is finally formed the side walls of the body and frame 35 will be parallel while the hood will have its side walls approaching one another towards the front and its top wall descending towards the front where the radiator is located.

35 It is a further object of my invention to provide such a lay out of blanks and dies that the minimum number of forming and piercing operations will be necessary.

40 It is an additional object to provide an interchangeable wind-shield.

45 It is an object to provide a fender which may be readily attached and detached for shipment and which will have its ends so

concealed by the wheels that they will not catch against the hands of the children operating the toys or catch in their clothes.

50 It is a further object to provide a one piece reinforced radiator which simulates the radiator on an automobile.

Referring to the drawings:

Fig. 1 is a plan view partially in perspective of the toy having a sedan body;

Fig. 2 is a plan view of the body blank in its initial stage;

Fig. 3 is a plan view of the body blank with 65 the doors, louvers, and edges of the frame formed;

Fig. 4 is a plan view partially in perspective showing the body blank formed to provide the double tapered hood, side frame 70 members, and the side walls of the body;

Fig. 5 is the radiator blank;

Fig. 6 is the completed radiator;

Fig. 7 is the wind-shield, dash board, and sun shade blank;

Fig. 8 is a perspective of the wind-shield blank finally formed;

Fig. 9 is the blank for the running board and fender on one side of the car;

Fig. 10 illustrates the blank after the first 80 forming operation;

Fig. 11 represents the blank after the last forming operation;

Fig. 12 represents the lamp blank;

Fig. 13 represents the completed lamp;

Fig. 14 is the sedan body blank;

Fig. 15 is the sedan body blank formed just prior to bending into shape for assembly;

Fig. 16 is a rear elevation of the sedan body 90 showing the blank forming a part of the rear panel of the body and showing one wall in position on the left hand and the right hand wall about to be put in position;

Fig. 17 is a side elevation of a partially 95 completed rear wall of the sedan body and gasoline tank.

It will be understood that the primary purpose of this invention is to provide in a few pieces a toy which may be shaped to 100 exactly resemble an automobile. The problem which I have solved has been to select the minimum pieces which can by successive die operations assume in single blanks a number of different configurations. It is 105 also necessary to have the parts interchange-

able as far as possible, such as the fenders and the dies interchangeable as in the case of the dies for the fenders.

It will be realized that my invention is applicable not only to toys but to the manufacture of other articles such as automobiles, whereas in a cheaper class of vehicles the same problems are presented and the same economies are necessary.

10 Referring to the drawings in detail:

The body of the automobile consisting of the side walls, frame members and hood are formed with a single piece. The hood portion of the blank from which these parts are formed is designated 1, and has on its forward end ears 2 which later become the forward ends of the side frames 3.

At the rear of this hood portion are V-shaped slots 4 which partially separate the 20 hood portion from the side walls of the body designated 5. These side walls have their adjacent outer ends curved as at 6, while their outer walls are notched as at 7 and 8 to receive the axle and mechanism customarily employed in such toys.

25 The next step is to form the embossed door outlines, 9, the louvers 10, and the side walls 11 of the hood. A flange 12 is also formed along the outer edge of the frame portion of the blank. The forward ends of the frame portion are pierced at 13 and 14 for the reception of the front axle and the bumper, respectively. The blank is then formed as in Fig. 4 with the side walls 5 30 parallel to one another and with the hood tapering inwardly and downwardly towards the front of the blank. This results in a ledge of triangular shape designated 15 being formed on either side of the hood.

40 In Fig. 5 will be seen a blank for the formation of a radiator. The front of the radiator is designated 16 on which there are formed a series of indentations 17 to represent the honey-comb of the radiator. Flanges 18 and 19 are provided for engagement with the radiator and the hood.

45 The blank illustrated in Fig. 7 is the wind-shield blank which is designated 20 and has cut therein an I-shaped slot 21. The upper edge of the blank 22 is convex to fit the roof of the sedan body and the lower edge is concave as at 23 to fit the top of the hood.

50 A part of the blank is turned inwardly as at 24 to form the dash board and another portion 25 is formed outwardly to form a sun shade.

The fenders are formed as follows:

55 A strip of metal 26 is provided with a series of teeth 27 at one end, a projecting rectangular portion 28 near the middle thereof on one side and a series of teeth designated 29, 30, 31 and 32 at the other end.

60 This second series of teeth have their outer edges so formed that the teeth make a triangular group.

In Fig. 10 it will be seen that these teeth are formed at right angles to the main body of the blank, while at the other side a flange 33 has been formed which encircles the blank until the flange meets the teeth on either 70 end.

A rectangular portion 28 is also made at right angles to the main body of the blank. In Fig. 11 it will be seen that the fenders have been arched. The fenders are attached 75 to the chassis or body hereinbefore described, by riveting or welding the teeth to the body. Head lamps are formed out of the blank 34 by cupping the blank as at 35. These head lamps are mounted upon the 80 fenders.

Referring to the formation of the sedan body, the body of the blank in Fig. 14 is designated 36. On either side are the side walls 37 formed integral with the top a 85 portion of the length of the top and separated from the remainder of the top by V-shaped cutaway portions 38. The side walls are formed with windows 39 and arch shaped cutaway portions 40 to receive the 90 fender and wheels at the rear of the body. The top is provided integral therewith with a rear panel 41. The line of division between the panel and the top is indicated 95 by notches 42. A rear window 43 is formed in the rear wall 41.

The lower end of the rear wall 41 has a blank for the purpose of being formed into a gasoline tank, or an imitation one. This blank is designated 44, and is provided with 100 ears 45 on either side thereof which are spaced from the rear wall 41.

The second general step in the formation of this sedan body is to bend the walls 46 and to punch in the windows 47 to form 105 frames. Flanges 48 are also formed on the forward edge of the body side walls for engagement with the wind-shield and body of the chassis of the machine. Inwardly bent flanges on the bottom of the side walls 110 as at 49 are formed to facilitate the engagement of the body with the chassis. Likewise, the flanges 50 which are arch shaped serve to form a suitable means of engagement between the fender and the side walls 115 of the body. The flanges 51 and 52 on the sides of the top and rear wall are used for the simple purpose of forming overlapping members which enable the several parts to be joined together.

120 The ears 45 are bent up at right angles to the blank 44, while a curve 53 is placed in the space between the ears and the rear wall 41 of the blank 44, thus defining the edge of the imitation gasoline tank. The rear edge of the blank 44 is bent at right angles to the ears 45 as at 54 to complete the illusion.

125 It will be understood that I do not desire to be confined to the details of my invention.

tion, but comprehend within it suitable modifications which may be found convenient in adapting my invention to varying conditions.

5 This application is a division of Serial No. 598,902.

Having thus fully described my invention, what I claim as new and desire to secure by Letters Patent, is:—

10 1. A blank for the bodies of toy vehicles formed from a single piece of sheet metal and comprising a central portion having its main portion shaped to conform to the top of the toy vehicle and an end extension 15 shaped to form the rear of the vehicle body and provided with a window opening, and side wings each formed integrally at one end of the main portion of the central portion and provided with door and window 20 openings.

2. A blank for the bodies of toy vehicles formed from a single piece of sheet metal and comprising a central portion having its main portion shaped to conform to the

25 top of the toy vehicle and an end extension shaped to form the rear of the vehicle body and provided with a window opening, and side wings each formed integrally at one

end of the main portion of the central portion and provided with door and window 30 openings, the peripheral portions of said blank being provided with notched flange forming extensions adapted for connection to other portions of the toy.

3. A blank for the bodies of toy vehicles 35 formed from a single piece of sheet metal and comprising a central portion having its main portion shaped to conform to the top of the toy vehicle and an end extension 40 shaped to form the rear of the vehicle body and provided with a window opening, and side wings each formed integrally at one end of the main portion of the central portion and provided with door and window 45 openings, the peripheral portions of said blank being provided with notched flange forming extensions adapted for connection to other portions of the toy, the wings and end extension of said blank being bent downwardly at right angles to the main top 50 to form the sides and ends of the vehicle body.

In testimony whereof, I affix my signature.

CLARENCE E. FLORKEY.
